METHOD FOR PRODUCING L-SORBOSE

CROSS REFERENCE TO RELATED APPLICATION

This application is related to copending application Ser. No. 285,265, filed Aug. 31, 1972, Makover and Pruess.

BACKGROUND OF THE INVENTION

The compound L-sorbose, which has the formula:

is disclosed in U.S. patent application Ser. No. 285,265, filed Aug. 31, 1972, as an intermediate for 2-keto-L-gulonic acid and can be converted to 2-keto-L-gulonic acid by various enzymatic means. Kondo and Ameyama have disclosed in Reports of Department of Agriculture, Shizuka University, volume 7, page 139 (1957) a pathway from L-sorbose to L-sorbose utilizing *Acetobacter suboxidans*. However, it has long been desired to utilize other microorganisms for producing L-sorbose.

SUMMARY OF THE INVENTION

In accordance with this invention, it has been found that L-sorbose can be produced from L-sorbose by the microbiological oxidation of L-sorbose from a microorganism selected of the following genera:

Gluconobacter;
Pseudomonas;
Acinetobacter;
Bacillus;
Sarcina;
Streptomyces;
Serratia;
Aerobacter;
Mycobacterium; and
Paecilomyces.

DETAILED DESCRIPTION

The novel process of this invention involves the one step microbiological conversion of L-sorbose to L-sorbose.

Any microorganism of the aforementioned genera can be utilized in accordance with this invention. Among the preferred strains are included: *Acinetobacter calcoaceticus* (ATCC 10153) *Bacillus* sp. strain TA (ATCC 27860)

Streptomyces cellulocae (ATCC 3313), (*Serratia* sp. (ATCC 93), *Serratia marcescens* (ATCC 27857), *Aerobacter aerogenes* (ATCC 27858), *Sarcina lutea* (ATCC 9341), *Pseudomonas putida* (ATCC 21812), *Gluconobacter melanogenus* (IFO 3293), *Mycobacterium phlei* (ATCC 355); and *Paecilomyces varioti* (ATCC 26820).

The strains of these species are publicly available in culture collections, both in the United States and abroad at ATCC (American Type Culture Collection) Washington, D.C. and IFO (Institute for Fermentation) Osaka, Japan. Mutant strains of the above mentioned

microorganisms have superior ability relative to the former wild strains to transform L-sorbose to L-sorbose. These mutant strains can be produced from the wild strains by mutagenic treatments. Such mutation can be caused by treating a wild strain with a mutagen such as ultra-violet irradiation, X-ray irradiation or contact with nitrous acid, or by isolating a clone occurring by spontaneous mutation. These means for inducing the desired mutation on a wild type strain may be effected in any of the ways per se well known for this purpose by one skilled in the art. Many of these methods have been described in various publications, for example, "Methods in Medical Research" Vol. 3, edited by R.W. Gerard, published by the Year Book Publishers, Inc., Chicago, U.S.A., in 1950, and "Nature" Vol. 183, p. 1829 (1959) by F. Kaudewitz.

The production of L-sorbose is effected by the cultivation of one of the above genera of microorganisms in an aerated deep tank, i.e., under submerged fermentation. The fermentation should be conducted at pH values of from about 5 to about 9 with pH values of from about 6.5 to about 7.5 being preferred. It is particularly preferred to carry out the process of this invention at a pH of from 7 to 7.2. Although the temperature is not critical, best results are usually obtained utilizing temperatures of from 20° to 45°C., with temperatures of from about 25° to 35°C. being particularly preferred. In general, about one to ten days are required to obtain the best results and from about 1 to 2 days are found most suitable.

The method of the present invention can be carried out by culturing the microorganism in a medium containing appropriate nutrients and L-sorbose. On the other hand, the process of this invention can be carried out by culturing the microorganisms and then, after culturing, bringing the whole cells or the cell free extract prepared from the culture into contact with L-sorbose.

In the case where the microorganism is cultured in a medium containing L-sorbose and appropriate nutrients, the microorganism may be cultured in an aqueous medium in an aerated fermentor. The cultivation should be conducted at pH values of from about 5 to about 9, with pH's of from about 6.5 to 7.5 being preferred. Especially preferred is utilizing a pH of about 7.0 to 7.2. A preferred temperature range for carrying out this cultivation is from about 20° to about 45°C. with temperatures of from about 25° to 30°C. being especially preferred. While the time for cultivation varies, with the kind of microorganisms and nutrient medium to be used, about 1 to 10 days cultivation usually brings about most preferable results. Concentration of L-sorbose in the media varies with the kind of microorganism, is generally desirable to be about 1 to 150 grams/liter, most preferably from about 2 to about 70 grams/liter.

It is usually required that the culture medium contains such nutrients for the microorganism as assimilable carbon sources, digestible nitrogen sources and preferably inorganic substances, vitamins, trace elements, other growth promoting factors, etc. L-sorbose per se can serve as the carbon source, but it is preferred to utilize other substances as carbon sources. Among the substances which can be utilized as carbon sources are included starch, cane sugar, lactose, dextrin, glycerol, maltose, etc. They can be employed at a concentration of from about 1 g./l. to about 10 g./l. As the ni-

rogen sources, there may be used various organic or inorganic substances such as soybean meal, meat extracts, peptone, casein, yeast extracts, corn steep liquor, urea, nitrates, ammonium salts, etc. As the inorganic nutrients, for example, potassium phosphates, magnesium sulfate, ferrous and ferric chlorides, calcium carbonate, etc., are usually employed. As the constituents of the medium vary also with the kind of microorganisms to be employed, it is preferable to choose a proper medium case by case.

In the case where after cultivation, the whole culture, i.e., the cells collected from the culture are brought into contact with the L-sorbose cultivation of the microorganisms is carried out under similar conditions described above. Substances mentioned above can, if desired, also be used for nutrients for this cultivation.

On the other hand, no nutrients need be present in cultivating the microorganisms. The whole grown culture is then utilized to convert L-sorbose to L-sorbosone. This conversion can be simply carried out in an aqueous medium under submerged conditions utilizing a pH of from about 5 to 9. In this conversion, no additional nutrients need be present.

Generally, from about 1 to 3 days culture is preferable for obtaining the most effective cells for the conversion of L-sorbose to L-sorbosone. In one case, L-sorbose or its aqueous solution is added to the cultured medium to make its final concentration from about 1 g./l. to about 200 g./l. The mixed solution may be incubated for about 1 to 10 days under the same conditions as discussed above. In another case, the cells may be collected by centrifugation from the cultured broth and resuspended in an aqueous medium at a pH of from about 5 to 9. Then L-sorbose is added in the same way as mentioned above. The succeeding incubation may be effected under similar conditions as those described above.

On the other hand, when cell free extracts from the whole grown culture are utilized, these cell free extracts can be utilized to convert L-sorbose to L-sorbosone by treating L-sorbose with the cell free extracts in an aqueous medium at a pH of from 5 to 9. In this case, no nutrients need be present.

Where the whole cells or the cell free extract are utilized to convert L-sorbose to L-sorbosone, this conversion is generally carried out with no additional nutrients being present. However, if desired, any of the conventional nutrients such as those mentioned hereinbefore may be added to the aqueous fermentation medium containing either the whole grown cells or the cell free extract. Furthermore, in carrying out the microbiological conversion of L-sorbose with whole grown cells or with cell free extract, temperatures are not critical. However, it is generally preferred to utilize incubating temperatures of from 20° to 40°C. Generally, this microbiological conversion is carried out at a pH of from 5 to 9.

The reaction can be stopped by freezing the reaction medium, i.e., cooling the reaction medium to a temperature of 0°C. or below to convert. Any temperature of 0°C. or below can be utilized to stop the reaction. Generally, temperatures of from -5° to -50°C. are utilized to stop the reaction. If desired, the L-sorbosone can be isolated by separating it from the reaction medium. Any conventional separation means can be utilized to carry out this isolation procedure. Among the preferred methods of isolation is by chromatography such

as paper chromatography, or column chromatography.

On the other hand, the L-sorbosone in the reaction medium need not be isolated but can be converted directly to 2-keto-gulonic acid in accordance with the disclosure in Ser. No. 285,265, filed Aug. 31, 1972.

The following examples are illustrative of the invention. All temperatures are in degrees centigrade.

EXAMPLE 1

Enzyme prepared from *Pseudomonas putida*

Pseudomonas putida 190B (ATCC 21812) (20 ml. inoculum) were inoculated in 6 liter flasks containing 2 liters of a medium containing the following:

	g./l. of distilled water
Ammonium sulfate	0.28
Sodium sulfate	2.5
K ₂ HPO ₄	10
KH ₂ PO ₄	5
Sodium citrate	5
CaCl ₂ · 6H ₂ O	0.025
FeCl ₃ · 6H ₂ O	1×10^{-3}
ZnCl ₂	5×10^{-4}
CuCl ₂ · 2H ₂ O	5×10^{-4}
MnCl ₂ · 4H ₂ O	5×10^{-4}
MgCl ₂ · 6H ₂ O	0.2
L-sorbose	4
Glycerol	5

The pH of the medium was adjusted to 7 and the medium was then autoclaved for 15 minutes at 15 p.s.i. and a temperature of 151°C. After autoclaving the cultures were grown in the flasks by aeration on a shaker at approximately 280 RPM at 28°C. for 8 hours. Cell-pellets were obtained by centrifugation for 15 minutes at approximately 10,000 $\times$ gravity. The cell-pellets were pooled and resuspended in 500 ml. of cold 0.02M aqueous sodium phosphate buffer pH 7.0 and the suspension centrifuged again. The precipitates obtained were pooled and resuspended in 50 ml. of 0.02M aqueous sodium phosphate buffer pH 7.0 and processed twice through a French press 14,000 lb. per sq. inch. The resulting cell-extracts were centrifuged at approximately 27,000 $\times$ gravity for 30 minutes. The supernatants obtained after removal of debris were dialyzed twice against 0.02M aqueous sodium phosphate pH 7.0 containing 1×10^{-3} M ethylenediamine tetraacetic acid (EDTA) and then dialyzed against buffer without EDTA. The resulting preparation designated dialyzed fraction 1, was used as given below.

Reaction mixtures were prepared containing in a total volume of 1.0 ml. of following:

Sodium phosphate, pH 7.0	40 μ mole
L-sorbose ¹	2.95×10^{-2} μ mole
Dialyzed fraction 1	15 mg. (protein)
¹⁴ C-labelled L-sorbose (1 μ Ci; sp. act: 34 mCi/mM).	

To each of these reaction mixtures, there was added L-sorbosone at different concentrations as given in the table below. The reaction mixture was incubated aerobically for 6 hours at 30°C. Analysis for ¹⁴C-labelled L-sorbosone was carried out by paper chromatography utilizing the following method.

A 50 μ l portion of each of the incubated reaction mixtures were applied to Whatman 3 MM paper (ascending) and developed for 18 hours with the following solvents: ethyl acetate, pyridine, water, acetic acid 5/5/3/1 parts by volume. L-sorbosone (R_f = 0.33) and

L-sorbosone ($R_f = 0.50$) are clearly separated by this system. The developed strips (50×5 cm) were air dried and then cut along the width into 1 cm segments. The folded segments were placed in vials for radioassays using a scintillation counter. Authentic samples of L-sorbosone and L-sorbose used as markers were located on the developed chromatograms by spraying with a silver nitrate solution or by location of the radioactive authentic markers through radioassays counted in a scintillation counter. From the counts, the weight percent of L-sorbose converted to L-sorbosone were determined as given in the table below:

Table 1

L-sorbosone added to the reaction medium (μ moles)	weight of L-sorbosone synthesized per weight of L-sorbose present in reaction medium (%)
2.13×10^{-5}	1.46
2.13×10^{-2}	1.37
2.13	1.14

EXAMPLES 2 through 5

The organisms listed in Table 2 were grown in either Medium 1 or Medium 2. The composition of Medium 1, which was adjusted to a pH of 7, was as follows:

	Grams/Liters of Distilled Water
Glucose	5
Yeast Extract	5
Beef Extract	5
Difco bacto Peptone ²	5

The composition of Medium 2 was as follows:

	Grams/Liters of Distilled Water
Difco bacto Peptone ²	6
Glucose	1
Yeast Autolysete	3
Beef Extract	1.5
N-Z Amine A ³	4

²A mixture of amino acids and peptides.

³A mixture of amino acids and peptides formed by the enzymatic hydrolysis of casein.

Example	Organism	No.	Conversion of L-Sorbose to L-Sorbosone			Percent Conversion of L-Sorbose to L-Sorbosone based upon L-Sorbosone added reaction medium
			Grown in Media	Ion In Cell-Free Extract	0	
1	Serratia s.p.	ATCC 93	1	Potassium	1.9	1.4
2	Serratia s.p.	ATCC 93	2	Sodium	1.0	0.6
3	Bacillus s.p.	ATCC 27860	1	Potassium	0.5	—
4	Bacillus s.p.	ATCC 27860	2	Potassium	0.2	0.6
5	Sarcina lutea	ATCC 9349	2	Potassium	0.4	0.4
6	Streptomyces cellulosae	ATCC 3313	2	Sodium	0.3	0.3
7	Serratia marcescens	ATCC 27857	2	Sodium	0.3	0.1
8	Aerobacter aerogenes	ATCC 27858	2	Potassium	1.1	1.0
9	Aerobacter aerogenes	ATCC 27858	2	Sodium	3.3	3.7
10	Aerobacter aerogenes	ATCC 27858	1	Sodium	2.9	1.5

* μ moles of L-Sorbosone added to the reaction mixture.

Inoculations were performed by transferring a loopfull of each culture from agar slants into 100 ml. of one of the two media in 500 ml. flasks. All cultures were grown with aeration on shakers (approximately 250 RPM) for 24 hours at 35°C, with the exception that *Serratia marcescens* was grown at 28°C, for 48 hours. After the growth period, each culture was split into equal parts and centrifuged at approximately 10,000 times gravity for 15 minutes, at 4°C. Each of the precipitates of the organisms was washed once with a buffer, i.e., either cold 0.02M aqueous sodium phosphate (pH 7.2) or cold 0.02M aqueous potassium phosphate (pH 7.2). The resulting buffered mixtures were then centrifuged as above. The precipitates were resuspended in 5 ml. of either of the buffers. Cell-extracts were prepared from each of the suspensions as in Example 1 except that only one passage through the French press was utilized.

In addition, all extracts so prepared were dialyzed at 20 4°C, either twice against 0.02M aqueous sodium phosphate buffer (pH 7.2) containing 1×10^{-3} M ethylene diamine tetraacetic acid EDTA followed by twice against the same buffer devoid of EDTA or twice against 0.02M potassium phosphate buffer containing 25 1×10^{-3} M EDTA buffer containing 1×10^{-3} M EDTA which was followed by twice against the last buffer devoid of EDTA to obtain the resulting cell-free extract preparation. The use of potassium phosphate or sodium phosphate is indicated in the following table:

30 Reaction mixtures containing each of the cell-free extracts prepared above were prepared with a volume of 1 ml. and a pH of 7.0 and containing the following ingredients:

35 L-sorbose⁴ 1 μ Ci
Cell-free Extract 0.5 ml.
Aqueous sodium or potassium phosphate 50 μ moles
4 ¹⁴C-Labelled L-sorbose (72 mCi/mMole)

40

To these reaction mixtures there was added L-sorbosone at sufficient concentrations as given in the table below. The reaction mixtures were incubated aerobically for 6 hours at 30°C. The reactions were terminated by freezing at -20°C. Analysis for L-sorbosone was carried out by the method given in Example 1. The results are given in Table 2. In this table *Bacillus s.p.* was the strain TA.

Table 2

EXAMPLE 6

Pseudomonas putida (ATCC 21812) (20 ml. inoculum) were inoculated in 6 liter flasks containing 2 liters of a medium which contains the ingredients and the amounts set forth in Example 1.

The pH of the medium was adjusted to 7 and the medium was then autoclaved for 15 minutes at 15 p.s.i. and a temperature of 151°C. After autoclaving, the cultures were grown in the flasks by aeration on a shaker at approximately 250 RPM at 28°C. for 18 hours. Cells were harvested by centrifugation for 15 minutes at approximately 10,000 $\times$ gravity. The cells were pooled and resuspended in 500 ml. of cold 0.02M aqueous sodium phosphate buffer pH 7.0 and the suspension centrifuged again. The washed cells obtained were pooled and resuspended in 50 ml. of 0.02M aqueous sodium phosphate buffer pH 7.0 and processed twice through a French press 14,000 lb. per sq. and extracts centrifuged at 27,000 $\times$ gravity for 30 minutes. The resulting supernatant, i.e. cell free extract was centrifuged at approximately 160,000 $\times$ gravity for 90 minutes. The supernatant obtained was designed as the "soluble fraction"; it was centrifuged again at high speed and the precipitate was discarded.

Reaction mixtures were prepared containing in a total volume of 1.0 ml. the following:

Sodium phosphate, pH 7.0	50 μ mole
L-sorbose ⁵	1.4 $\times$ 10 ⁻² μ mole
Soluble fraction	9.4 mg.
¹⁴ C-labelled L-sorbose (72 MCi/mM)	

In some of the reaction mixtures there was placed NAD⁺ [nicotinamide-adenine dinucleotide (oxidized)] as a cofactor. In other reaction mixtures there was placed NADP⁺ [nicotinamide-adenine dinucleotide phosphate (oxidized)] as a cofactor. On the other hand, reaction mixtures were prepared without a cofactor. Where the cofactor was present, it was present in an amount of 1.4 μ mole per 1.0 ml. of reaction mixture.

The reaction mixture was incubated aerobically for 7 hours at 30°C. An analysis for ¹⁴C-L-sorbose was carried out by paper chromatography utilizing the method described in Example 1. From the counts, the moles of L-sorbose converted to L-sorbose was determined as given in the table below:

Table 3

Reactions	Cofactor	% of total counts in ¹⁴ C-L-sorbose
I	None	0.3
II	NAD ⁺	0.5
III	NADP ⁺	0.2

EXAMPLE 7

By the procedure given in Example 2 through 5, utilizing *Paecilomyces varioti* (ATCC 26820) and *Mycobacterium phlei* (ATCC 355), L-sorbose was converted to L-sorbose.

In the case of *Mycobacterium phlei*, the medium 2

was utilized; the cation was potassium and 2.2 μ moles of L-sorbose was added to the reaction mixture. The percent conversion of L-sorbose to L-sorbose was 0.3%.

In the case of *Paecilomyces varioti*, the medium 1 was utilized, the cation was potassium and 2.2 μ moles of L-sorbose was added to the reaction medium. The percent conversion of L-sorbose to L-sorbose was 0.3%.

We claim:

1. A method for producing L-sorbose from L-sorbose which comprises pre-culturing under submerged aerobic conditions at a temperature of from 20° to 45°C. and a pH of from 5 to 9, a microorganism selected from the group consisting of:

Paecilomyces;
Mycobacterium;
Pseudomonas;
Serratia;
Bacillus;
Aerobacter;
Streptomyces;
Gluconobacter;
Sarcina; and
Acinetobacter,

in an aqueous medium to produce cells containing an enzyme system capable of converting L-sorbose to L-sorbose, incubating under submerged aerobic conditions at a temperature of from 20° to 45°C. and a pH of from 5 to 9, said cells with a medium containing L-sorbose to convert the L-sorbose to L-sorbose and recovering L-sorbose from said media.

2. The process of claim 1 wherein said microorganism is *Pseudomonas putida*.

3. The process of claim 1 wherein said microorganism is *Aerobacter aerogenes*.

4. A process for the preparation of L-sorbose which comprises pre-culturing, under submerged aerobic conditions at a temperature of from 20° to 45°C. and a pH of from 5 to 9, a microorganism selected from the group consisting of:

Pseudomonas;
Serratia;
Bacillus;
Aerobacter;
Streptomyces;
Sarcina;
Mycobacterium;
Acinetobacter;
Gluconobacter; and
Paecilomyces,

in an aqueous medium to produce cells containing an enzyme system capable of converting L-sorbose to L-sorbose, extracting said enzyme system from said cells and incubating this system, under submerged aerobic conditions at a temperature of from 20° to 45°C. and a pH of from 5 to 9, with a L-sorbose containing medium to convert the L-sorbose in the medium to L-sorbose.

5. The process of claim 4 wherein said microorganism is *Pseudomonas putida*.

6. The process of claim 4 wherein said microorganism is *Aerobacter aerogenes*.

* * * *
